UNITED STATES PATENT OFFICE.

ALEXANDER BERNSTEIN, OF LONDON, ENGLAND, ASSIGNOR OF ONE-HALF
TO CHARLES LEVY, OF LONDON, ENGLAND.

POCKET-SHIELD.

SPECIFICATION forming part of Letters Patent No. 726,850, dated May 5, 1903.

Application filed June 16, 1902. Serial No. 111,976. (No model.)

To all whom it may concern:

Be it known that I, ALEXANDER BERNSTEIN, a subject of the King of Great Britain, residing at 45 Seymour Place, Bryanston Square, London, England, have invented a new and useful Improved Pocket-Shield, of which the following is a specification.

My invention relates to a shield or protection for enabling fragile articles, especially 10 cigars, cigarettes, and the like, to be carried loose in the pocket of an ordinary vest or jacket without injury by friction against the garment or against other articles which may be placed in the same pocket.

15 My invention also provides a convenient means for carrying address-cards or the like.

The advantages of my device over the customary cases or holders for cigarettes or the like are principally that the fit of the garment 20 is not interfered with in any way by the use of the shield and that while providing a sufficient space to hold a quantity of cigarettes or the like it does not unduly increase the bulk of the pocket. Further, it can be instantly 25 removed or replaced, and its contents are quite as easily available as if they were carried entirely loose in the pocket.

My invention is illustrated in the accompanying drawings, in which—

30 Figure 1 shows an elevation of the apparatus viewed from the outside. Fig. 2 shows a horizontal section on the line A B of Fig. 1. Fig. 3 shows a vertical section on the line C D of Fig. 1. Fig. 4 shows a perspective view of the device in position in a pocket.

The shield comprises a curved metal plate 1, composed of a rectangular piece of metal which is curved to approximately correspond 35 with the curvature of the body. On each side of the metal plate the metal is turned over to form a rim 2, and upon the thickness of this rim the capacity of the apparatus will 40 depend. Practically I find it is convenient to give these rims the thickness of about one-quarter inch or a little more. At the middle 45 of the upper edge of the shield I usually cut a small depression 3 for convenience in guiding the fingers of the user to select a cigarette

or the like from the middle of the quantity contained within the shield. The metal 50 shield is usually covered with leather or other suitable or durable covering 6, and I prefer to add to it an outside pocket 4, as shown in Fig. 1, specially for the purpose of containing visiting-cards or other small and light objects. 55

The dimensions of my apparatus are obviously limited by the purpose for which it is applied, and in general it is most conveniently formed to fit the vest-pocket 5 and to contain 60 one or two rows of cigarettes or a proportional number of small cigars. The contents are thoroughly protected from being rubbed between the two sides of the pocket and also against blows or jars from the outside. They 65 are therefore preserved equally safely as if they were inclosed in a case, while being more conveniently accessible and taking up proportionately less room in the pocket. For special purposes larger or smaller size shields 70 may obviously be constructed.

Any desired embellishment, inscription, or the like may be placed on the inside or outside of the shield.

What I claim is—

1. In combination with a garment-pocket, a rectangular vertical shield for fragile articles, curved approximately to the shape of the body, recurved vertical rims on said shield, a cover on said shield, and rims, and a pocket 75 in the cover of said shield.

2. A protective pocket-shield for cigars, comprising in combination an approximately rectangular metal shield curved to the curvature of the body, vertical rims on said shield 80 inwardly curved to inclose an unobstructed space between the front of the shield and the inner side of the pocket and a cover adherent to the outside of said shield.

In testimony whereof I have signed my 90 name to this specification in the presence of two subscribing witnesses.

ALEXANDER BERNSTEIN.
